UNITED STATES PATENT OFFICE.

CHARLES A. BENHAM, OF CLEVELAND, OHIO, AND HUGH McLAUGHLIN, OF SUPERIOR, WISCONSIN.

RUDDER-INDICATOR.

1,110,737.

Specification of Letters Patent.

Patented Sept. 15, 1914.

Application filed March 8, 1913. Serial No. 752,810.

To all whom it may concern:

Be it known that we, CHARLES A. BENHAM, of Cleveland, Ohio, and HUGH McLAUGHLIN, of Superior, Wisconsin, have invented certain new and useful Improvements in Rudder-Indicators; and we hereby declare the following to be a full, clear, and exact description of the same, such as will enable others skilled in the art to which it appertains to make and use the same.

The object of our invention is to enable the wheelsman, pilot or other officer of the ship to ascertain at a glance the exact position of the rudder. For this purpose we provide a dial suitably mounted, and an index finger to indicate upon the dial the exact position of the rudder. The index finger is controlled by means of a double cylinder at the forward end of the ship and a double cylinder at the rear end of the ship near the rudder, the forward cylinder being operated by the rear cylinder through the means of liquid, preferably oil, passing from the rear cylinder to the forward cylinder by means of suitable pipe connections.

In the accompanying drawings Figure 1 is a plan view of the deck of a vessel showing the location of the mechanism in the pilot house and also the location of the mechanism at the after end of the ship forward of the rudder and the pipes connecting the same. Fig. 2 is an inverted plan view of the mechanism located at the stern of the vessel near the rudder. Fig. 3 is a side elevation of the same with flanges of the channel iron removed. Fig. 4 is a section at line x, x , Fig. 3. Fig. 5 is an end elevation of the structure shown in Fig. 3 omitting the cylinder and slide and rod Q shown in Fig. 4. Fig. 6 is a front elevation of that part of the mechanism located at the forward end of the ship. Fig. 7 is a sectional side view on line x, x , Fig. 6. Fig. 8 is a plan view of the structure shown in Fig. 6 omitting the check valves, the tank and connecting pipes. Fig. 9 is an enlarged sectional plan view of part of the structure in Fig. 8. Figs. 10 and 11 are details of the check valves shown in Fig. 6.

A is the frame of the indicator and is attached to the wall of the pilot house A^1 as indicated in Fig. 7. Mounted on each end of the frame A are metallic pieces B, B^1 , threaded to receive the pipes F, F^1 , which extend through the frame. The pistons E,

E^1 , are hollow as shown in Fig. 9 and are also secured to the parts B, B^1 . Opposite the pipes F, F^1 , the parts B, B^1 , are threaded to receive the bolts c, c^1 , for attaching the bar C. Mounted between the frame A and the bar C is the cylinder D. The cylinder D has two channels adapted to engage slides a^2, c^2 , permitting longitudinal movement of the cylinder. The cylinder D is bored from each end and is provided with stuffing boxes d^2 and d^3 . The pistons E and E^1 , are turned true and fitted into the ends of the cylinder D and stuffing boxes d^2 and d^3 . The upper surface of the cylinder D is provided with a rack or toothed portion d^4 adapted to engage the teeth at the lower end of the indicator finger a . Adjacent to the frame A the pipes G, G^1 , are connected with T's H, H^1 , and are also connected through a by-pass valve I. The pipes J, J^1 , lead from the T's H, H^1 , to the pistons P, P^1 , shown in Figs. 2 and 3, and located at the stern of the vessel.

h^2 is a pipe leading to the check valves K and L as shown in Fig. 6. The pipe M leads to an oil reservoir or tank R. The frame A is mounted on the wall of the pilot house A^1 (Fig. 7) by means of bolts projecting through the supports a^3, a^4 , and fastened at each end in any desired manner.

The mechanism at the stern of the vessel consists of the cylinder O mounted on the channel iron or frame N, (as shown in Fig. 2,) by means of the dovetailed slide N^1 . The cylinder O is provided at each end with stuffing boxes o, o^1 . The cylinder and stuffing boxes o, o^1 , are bored to receive the pistons P, P^1 , the cylinder being bored from each end, with a solid metal wall between the ends as shown in Fig. IX and in dotted lines in Fig. VIII. The pistons are turned true and rigidly mounted in the blocks n, n^1 , the blocks being in turn mounted on the frame N. The cylinder O is connected with the rudder tiller or quadrant T by means of the pin o^2 and rod Q.

The check valve K is an ordinary form of upright check valve inverted to permit the oil to flow into the cylinder and the connecting pipes, while the check valve L is provided with an adjustable spring l to permit the oil to return to the tank whenever by reason of adjustment or otherwise, there shall be an excess of pressure in either the right hand or left hand cylinders.

The operation of the device is as follows: The oil enters through the pipe M, the check valve K, pipe h^2 , into both ends of the cylinder D and from there through the connecting pipes into each end of the cylinder O, the rudder being placed amidships when the oil is admitted, and the pointer *a* being set to indicate the position of the rudder. The valve I is then closed. When the wheelsman shifts the rudder to port, the rod Q will pull the cylinder O in the direction of the part B and thereby move the index finger to the right hand indicating that the rudder has been moved to port. The displacement of the cylinders is so proportioned that the movement of the rudder to the full extent of its movement to port will move the finger to the extreme right of the dial, and the movement of the rudder to starboard to the full extent, will move the index finger to the extreme left of the dial, and thus the position of the rudder will at all times be accurately indicated on the dial by the pointer. It is immaterial what kind of fluid is used to operate the apparatus, but oil is preferable on account of freedom from freezing and also as being adapted to promote the smooth working of the pistons and as being less likely to leak at the stuffing boxes.

Having described our invention, we claim:

1. A rudder indicator for vessels the combination with the rudder of a double cylinder suitably mounted near the steering wheel, a double cylinder located and suitably mounted near the rudder, pipes filled with oil connecting the corresponding ends of said cylinders, a pointer connected with the forward cylinder, and an operative connection between the after cylinder and the rudder whereby the pointer through the ac-

tion of the cylinders and the oil moves with the rudder and indicates its position, substantially as and for the purpose specified.

2. A rudder indicator for vessels the combination with the rudder of a double cylinder suitably mounted near the steering wheel, a double cylinder suitably mounted near the rudder, pipes filled with oil connecting the corresponding ends of said cylinder, a pointer connected with the forward cylinder, a dial suitably marked and mounted near said pointer, and an operative connection between the after cylinder and the rudder whereby the pointer through the action of the cylinder and the oil moves with the rudder and indicates its position, substantially as and for the purpose specified. 45

3. In a rudder indicator for vessels the combination with the rudder of a double cylinder suitably mounted near the steering wheel, a double cylinder suitably mounted near the rudder, pipes filled with oil connecting the corresponding ends of said cylinders, an oil tank connected with said pipes, a pointer connected with the forward cylinder, a spring check valve between said pipes and the oil tank whereby upon an excess of pressure being produced in either side of the cylinders the oil is permitted to flow back into the tank until such excess of 50 pressure is relieved, substantially as and for the purpose specified. 55

In witness whereof we hereunto set our hands at Cleveland, Ohio, this 3rd day of March, 1913.

CHAS. A. BENHAM.
HUGH McLAUGHLIN.
